UNITED STATES PATENT OFFICE

SHELDON P. THACHER, OF DETROIT, MICHIGAN, ASSIGNOR TO MORGAN & WRIGHT,
OF DETROIT, MICHIGAN, A CORPORATION OF MICHIGAN

DESIGN FOR A TIRE

Application filed January 5, 1931. Serial No. 38,185. Term of patent 7 years.

To all whom it may concern:

Be it known that I, SHELDON P. THACHER, a citizen of the United States, residing at Detroit, county of Wayne, State of Michigan, have invented a new, original, and ornamental Design for Tires, of which the following is a specification, reference being had to the accompanying drawing, forming part thereof, wherein:

The figure is a perspective view of a portion of a tire showing my new design.

I claim:

The ornamental design for a tire as shown. Signed at Detroit, in the county of Wayne, and State of Michigan, this 16th day of December, 1930.

SHELDON P. THACHER.
